UNITED STATES PATENT OFFICE.

ARTURO DURAN, OF SAN ANTONIO, TEXAS.

SAFETY APPARATUS.

1,406,625.

Specification of Letters Patent. Patented Feb. 14, 1922.

Application filed July 29, 1919. Serial No. 314,065.

To all whom it may concern:

Be it known that I, ARTURO DURAN, a citizen of Mexico, residing at San Antonio, in the county of Bexar and State of Texas, have invented certain new and useful Improvements in Safety Apparatus, of which the following is a specification.

This invention relates to a combined signal and obstructor for street crossings.

10 The object of the invention is to provide mechanism to permit a vehicle reaching a street crossing first to have the right of way, and to automatically erect obstructions in the path of those coming from the other directions.

15 Another object is to construct such mechanism so that it will simultaneously erect an obstacle in the path of an approaching vehicle and operate a signal positioned in the center of the street, or other suitable point.

20 Another object is to so construct such mechanism that all the operating parts will be thoroughly protected against the weather and against tampering by unauthorized persons.

25 With the foregoing and other objects in view, which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention.

35 In the accompanying drawings:—

Figure 1 represents a plan view showing the relative positions of the parts constituting this invention located at the intersection 40 of two streets,

Fig. 2 is a horizontal section,

Fig. 3 is a plan view of the vehicle receiving platform with the top removed,

Fig. 4 is a side elevation thereof, the street 45 being shown in section,

Fig. 5 is a longitudinal section thereof.

The post or semaphore which is designed to be located at the center of each street crossing may be of any suitable construction and comprises principally a casing 1, which is adapted to be embedded in the ground for a purpose which will later appear. An upstanding post 9 extends vertically from the interior of the casing 1, and 55 its upper end is provided with a member 10 from which radiate plates or wings 12

containing various indicia to indicate the condition of the crossing.

The inner side walls of the casing 1 are provided at diametrically opposite points 60 with pairs of vertically spaced apertured lugs 15 to receive right angularly disposed links 16 which are pivotally mounted between the lugs at their angles. The free ends of the links 16 have engaged therewith 65 coiled springs 17, four of which are here shown and which are connected at their other ends with the free ends of similar links 18 and 19 pivoted at their angles to the opposite ends of a pair of arms 20 and 21 70 secured to the post 9.

Mounted on bolts 5 inside the casing 1, are four pulleys 22 around which pass chains 23. These chains also pass around the grooves formed in the ends of the arms 75 20 and 21 and are secured to the bolts 24. These chains pass out through the side walls of the casing into the tubes 25, four of which are shown arranged in pairs at diametrically opposite points and which are 80 bolted to the outer wall of the casing 1 as clearly shown in Figure 2. These tubes 25 extend from the casing 1 to the platforms 35, 36, 37 and 38 positioned at the corners of the street, as most clearly shown 85 in Figure 1; the chains 23 passing through said tubes for a purpose presently to be described.

The post or semaphore is located in the center of the street crossing as shown in 90 Fig. 1, the casing 1 thereof being located in a pit or hole in the street and is firmly secured therein by any suitable means. The normal position of the semaphore arms or wings 12 should be in the direction of the 95 corners of the street, and in the same direction as the axles of the pulleys 22. The protecting tubes 25 of the chains 23 are located below the surface of the pavement and are connected to the four platforms at 100 the corners of the streets A and B as is shown clearly in Fig. 1. These platforms are placed at the extremity of the right hand corner of each street and are mounted in pits or holes in the street as is shown clearly 105 in Fig. 4 so that they may move vertically in said pits, their surfaces or upper faces being normally flush with the pavement.

These platforms are all exactly alike, and hence one only will be described in detail. 110 Supported in the pit 39 is a frame mounted at one end on uprights 40 and at its

other end supported in notches or recesses 41 in the rear end wall of the pit as is shown clearly in Fig. 4.

Each of the platforms comprises two vertically movable members 42 and 60. The member 42 is pivotally mounted at its front end on standards 43 and is provided at its rear end with depending links 44 having slots 45 in their free ends. These slots 45 are engaged with studs 46 which project laterally from supporting beams 47 mounted in the pit. These beams or longitudinally disposed bars 47 are braced to the side bars 48 of the frame which is mounted 10 on the standards 40 and in their notches 41. These links 44 are also fulcrumed to levers 49 carried by a shaft 50.

A segment 51 is pivotally mounted on a shaft 52 supported in vertical alignment with 20 and below the shaft 50 as is shown clearly in Fig. 5, the upper corner of said segment being engaged with shaft 50. Mounted in longitudinal alignment with each segment 25 51 is a pulley 53, and supported in a frame 54 in advance or at the front end of the platform structure is another pulley 55 disposed in a plane at right angles to the pulley 53. The chain 23 entering through pipes 25, passes around these pulleys 55 and 53 and 30 up over the periphery of the segment 51 which is grooved to receive the chain, said chain being fixed to shaft 50, so that a pull exerted on the chain will operate to turn the shaft.

35 A shaft 56 is journaled in the side bars 48 of the platform supporting structure, and has mounted on its opposite ends bell crank levers 57, the shaft forming a fulcrum therefor. The short arm 58 of each of these levers is pivotally connected with a lug 59 depending from the front end of the platform member 60, the long arm 58^a of said bell crank is pivotally connected at 61 with one end of a link 62, it being understood that 40 these links 62 are in duplicate, one being arranged at each side of the platform. The other ends of these links 62 are engaged with the shaft 50 for a purpose presently to be described.

45 50 Heavy coiled springs 63 are mounted below the platform member 60 and operate to turn said member to operative position after depression.

55 A coiled spring 64 is connected at one end with a depending apertured lug 65 carried by the lower face of the member 60 near its rear end and at its other end said spring is engaged with a cross rod 66 supported in the side bars 48 of the frame. These springs are 60 made very heavy and powerful and are designed to return to normal position the platform 60 when weight is removed therefrom.

65 The springs 63 are also made powerful and are intended to raise the platform from the surface of the supporting frame, and

operate only at a weight of five hundred pounds, more or less.

Two pairs of twin links 67, preferably composed of steel, support the rear end of the platform member 60 permitting it to 70 move forward and backward.

The platform members 42 and 60 have covers, preferably of wood, on which the vehicles are designed to rest.

In the use of this invention, a vehicle coming down street B and reaching platform 75 35 before those coming in opposite direction on street A and street B, will be driven onto the platform 35 and depress the members thereof, which will exert a pull on the chain 80 23 leading from the front end of the platform, which in turn will operate to pull on one of the arms 20 or 21 according to which it is connected. This pull on the arm will operate to turn the post 9 and actuate the 85 signals carried by said post. The turning of the post will simultaneously exert a pull on the chain 23 of platforms 36 and 38 thereby forcing the front members 42 of said platforms into elevated position and causing 90 their rear members 60 to recede thereby giving an unobstructed road to the car which passes over platform 37.

The vehicle having passed from platform 95 35, the movements of the apparatus are reversed, lowering the obstacles or stop members 42 of platforms 36 and 38 and raising the front member 42 of platforms 35 and 37. The obstacles in the form of the platform members 42 are designed to rise to a height 100 of eighteen inches above the level of the street, more or less, retaining an inclined position toward the front and are intended to prevent the progress of cars passing over the respective platforms forming obstructions in 105 the path of the cars without danger of injuring them.

The apparatus functions at the moment when one of its four platforms is depressed, and they operate with a pressure or weight 110 of five hundred pounds, more or less.

From the above description it will be obvious that street crossings equipped with this apparatus will be absolutely safe against all possible collisions, and the semaphore which is located at the center of the crossing will indicate to pedestrians as well as to vehicles, the direction which may be traversed with safety.

From the foregoing description, taken in 120 connection with the accompanying drawings, the advantages of the construction and of the method of operation will be readily apparent to those skilled in the art to which the invention appertains and while I have 125 described the principle of operation of the invention together with the device which I now consider to be the best embodiment thereof, I desire to have it understood that the device shown is merely illustrative and 130

that such changes may be made as are within the scope of the claimed invention.

Having thus fully described my invention, what I claim as new and desire to secure by 5 Letters Patent, is:—

1. In a vehicle obstructing mechanism for intersecting roads, the combination of an ob- 65 structor placed near each corner of the intersection; a vehicle operated mechanism located adjacent each corner of the intersection, and connections between said vehicle operated mechanisms and ob- 70 structors, whereby actuation of one of said vehicle operated mechanisms will actuate the ob- structors located on the intersecting street.
  2. In a vehicle obstructing mechanism for a street crossing, a vertically movable platform located at each corner of the crossing, an obstructor in front of each platform, and 75 connections between said platforms, and ob- structors whereby a predetermined weight on one platform will actuate the ob- 80 structors of the intersecting street to locate them in the path of passing vehicles.
  3. In a vehicle obstructing mechanism for a street crossing, a vertically movable platform located at each corner of the crossing, an obstructor in front of each platform, and 85 connections between said platforms, and ob- structors whereby a predetermined weight on one platform will actuate the ob- 90 structors of the platforms located on the intersecting street to prevent their passage at the crossing.
  4. In a vehicle obstructing mechanism for a street crossing, a vertically movable platform located at each corner of the crossing, an obstructor in front of each platform, and 95 connections between said platforms, and ob- structors whereby a predetermined weight on one platform will actuate the ob- 100 structors of the platforms located on the intersecting street to prevent their passage at the crossing, without affecting the obstructor of the depressed platform or the one at the opposite corner.
  5. In a vehicle obstructing mechanism for a street crossing, a vertically movable platform located at each corner of the crossing, an obstructor in front of each platform, and 105 connections between said platforms, and ob- structors whereby a predetermined weight on one platform will actuate the ob- 110 structors of some of the others to locate them in the path of passing vehicles, and means for returning said platforms and ob- structors to normal position after the passage of the right of way vehicle.
  6. In a vehicle obstructing mechanism for 115 a street crossing, a vertically movable platform located at each corner of the crossing, an obstructor in front of each platform, and
- connections between said platforms, and ob-
structors whereby a predetermined weight
on one platform will actuate the ob-
structors of the platforms located on the intersecting street to prevent their passage at the crossing, without affecting the obstructor of the depressed platform or the one at the opposite corner.
7. In a vehicle obstructing mechanism for intersecting roads, the combination of an ob-
structor placed near each corner of the intersection; a vehicle operated mechanism located adjacent each corner of the intersection, connections between said vehicle operated mechanisms and the ob-
structors whereby a pre-determined weight on one vehicle operated mechanism on one road will actuate the ob-
structors located on the intersecting road, and means for automatically returning the vehicle operated mechanism and ob-
structors to their normal positions after said weight has been removed.
8. In a vehicle obstructing mechanism for intersecting roads, the combination of an ob-
structor placed near each corner of the intersection; a vehicle operated mechanism located adjacent each corner of the intersection, connections between said vehicle operated mechanisms and the ob-
structors, said connections comprising a cable for each vehicle operated mechanism, and a spring retained rotatable member connected to said cables whereby actuation of one of said vehicle operated mechanisms on one road will 100 actuate ob-
structors located on the intersecting road.
9. In a vehicle obstructing mechanism for intersecting roads, a vertically movable platform located at each corner of the intersection, an obstructor in front of each platform, connections between said platforms and ob-
structors, whereby actuation of one platform on one street will actuate ob-
structors located on the intersecting road or street, an oscillatory part associated with each platform, a bell crank connected to each platform, a link connected to each bell crank and each oscillatory part, and a slotted link connected to each ob-
structor and each oscillatory part, 110 whereby depression of a platform on one side of the road elevates an ob-
structor on the intersecting road.

In testimony whereof I affix my signature in presence of two witnesses.

ARTURO DURAN.
